UNITED STATES PATENT OFFICE

ERNEST W. DAVIS, OF OAK PARK, ILLINOIS, ASSIGNOR TO ALEMITE CORPORATION, OF CHICAGO, ILLINOIS, A CORPORATION OF DELAWARE

LUBRICATING APPARATUS

Application filed January 14, 1928, Serial No. 246,739. Renewed April 6, 1931.

My invention relates, generally, to lubricating apparatus and more particularly to pneumatically-operated lubricant compressors and means for controlling their operation.

5 It is an object of my invention to provide an improved pneumatically-operated compressor in which the energy for the compression stroke of the plunger is derived from its momentum.

10 A further object is to provide an improved pneumatically-operated compressor which is simple in construction, has a minimum number of moving parts, and which may be economically manufactured.

15 A further object is to provide an improved compressor in which the presence of air in the lubricant does not prevent its efficient operation.

20 A further object is to provide a lubricant compressor, the operation of which is not hindered by the presence of foreign material in the lubricant.

25 A further object is to provide improved controlling means for the compressor whereby it will operate to build up a predetermined pressure and cease operation as soon as that pressure has been reached.

30 A further object is to provide an improved quick snap-over air valve.

Other objects will be apparent from the following description, reference being had to the accompanying drawings, in which

35 Fig. 1 is an elevation of my improved lubricant compressor and controlling mechanism;

Fig. 2 is a plan view thereof;

Fig. 3 is a central vertical section thereof taken on the line 3—3 of Fig. 2;

40 Fig. 4 is a horizontal section taken on the line 4—4 of Fig. 3;

Fig. 5 is a vertical section taken on the line 5—5 of Fig. 3; and

45 Figs. 6 and 7 are vertical sectional views of the plunger and cylinder, the plunger being shown in its two extreme positions.

50 My improved compressor comprises a cylindrical container 8 having a cover 10 and a bottom 12 which is secured to a suitable cylinder casting 14 by bolts 16. The cylinder

casting 14 is detachably secured to a base 18 by a cap screw 20. A follower 22 having a handle 24 is adapted to rest upon the top of the lubricant and cause even feeding of the lubricant from all portions of the container 8. The container 8 is secured to the bottom 12 in any suitable manner as by having the lower edge of the cylindrical container rest in a groove 26 formed in the bottom 12 and wedging it therein by calking of lead or similar material.

55 The cylinder casting 14 has a suitable supply chamber 28 therein which is in direct communication with the lubricant in the container 8. While the compressor may be used with other lubricants, it is particularly designed for the supply of grease under high pressure, and the term "grease" will herein-after be used as including all similar substances.

60 A cylinder 30 is formed in a bored plug 32 which is threaded in the cylinder casting 14. The right-hand end portion of the plug 32 (Figs. 3, 6 and 7) is hardened to the degree of tool steel. A check valve 34 is held against an annular seat 36 by a compression spring 38, the other end of which rests against a shoulder formed in a union 40 to which the outlet conduit 41 is connected. The seat 36 has a sharp edge formed by the intersection 70 of the cylindrical surface 30 with the beveled surface of a shoulder. The angle of this bevel is slightly exaggerated in the drawings. As best illustrated in Fig. 5, the valve 34 has a plurality of guiding lugs 42 which serve 75 properly to space the valve over its seat and permit the passage of lubricant when the valve has been raised from its seat. This valve is a thin metal disc and thus very light in weight so that its action is very rapid.

80 A plunger 44 is guided in a cylindrical bore 46 formed in the casting 14 which is in registry with the cylinder 30. The left-hand portion of the bore 46 is slightly tapered, as shown at 48, this taper forming a recess for 85 the collection of grease as the plunger 44 moves to the right. This collection of grease, which is drawn along with the plunger, forms a tight seal around the plunger so that no packing is required. The plunger 44 is rig- 100

idly secured to an air piston 50 which is reciprocable within a cylinder 52 formed with in a sideward extension 54 of the casting 14. The piston 50 has a portion 56 of smaller 5 diameter than the cylinder 52 which is guided in a bore 58 formed in the extension 54. The end of the cylinder 52 is closed by a suitable castellated plug 60 which is held against rotation by a pin or wire 62. The cylinder 10 52 has an inlet port 64. The piston 50 has an annular face 66 which is normally subjected to the pressure of the air entering the cylinder through the port 64. The piston 50 has an axial bore 68 and has a plurality of 15 radial passages 70 connecting the bore 68 with the annular space 72 between the piston 50 and the walls of the cylinder 52.

The supply of air for operating the piston 50 is provided from any suitable source 20 through a pipe 74, which may be shut off by a globe valve 75, the pipe being threaded in a bushing 76, and the bushing being threaded in an air valve body 78. The bushing 76 has a plurality of slots 80 cut in its lower end 25 which permit passage of air past a ball 82 which is normally held against the end of the bushing 76 by a spring 84. A valve seat 86 is provided in the body 78 and is adapted to be covered by the ball 82 thereby to prevent 30 passage of air from the conduit 74 to a conduit 88 which is in communication with a chamber 90 formed beneath the valve seat 76. The conduit 88 is connected to the inlet opening 64 of the air cylinder. The compression 35 of the spring 84 is controlled by the pressure in the grease discharge conduit 41 which acts upon a cup leather piston 92 which is rigidly secured to a stem 94, the upper end of which is shouldered to form a seat for the spring 40 84. The cup leather piston 92 is reciprocable in a cylinder 96 formed in a casting 98 which is threaded to the lower end of the body 78.

Suitable packing 100 is compressed between 45 the casting 98 and the body 78 to form a stuffing box for the rod 94. The discharge conduit 41 is connected to supply lubricant to the upper end of the cylinder 96. A conduit 102 is also connected at the upper end 50 of the cylinder 96 and leads to any suitable means which may be used to supply the grease to the bearings. The stem 94 is normally held in its uppermost position by a spring 104, the lower end of which rests upon a plug 106 threaded in the lower end of the casting 98 and the upper end of which engages a member 108 which has a projection 110 protruding into the bore of the cylinder 92 and which engages the end of the stem 94.

60 The compressor is adapted to be used where a supply of air under moderate pressures is readily available and where it is desired to supply grease under high pressures for application to bearings. The compressor 65 is adapted to maintain grease under high

pressure in the discharge conduit automatically, accomplishing this purpose by automatically controlling the admission of air to the air cylinder.

In operation, the supply pipe 74 is connected to the source of air under pressure and the air will normally flow past the ball valve 82, through the conduit 88, into the annular space 72 of the air cylinder and thereafter through the radial passages 70 to 70 the right-hand end of the cylinder 52. Since the effective area of the right-hand end of the piston 50 (Fig. 3) is greater than the area of the annular shoulder 66 formed between the enlarged end of the piston and the portion 56 of the piston, the piston will be forced to the left, from the position shown in Fig. 3, until the admission of air to the right of the piston is cut off by the movement of the passageways 70 past the end of the annular 75 space 72. The piston 50 and plunger 44, however, will have acquired sufficient momentum to carry the end of the plunger 44 into its cylinder 30 and force the grease past the check valve 34 and into the discharge conduit 41. During the latter portion of this leftward movement of the piston 50, the air in the annular space 72 will be compressed and form a cushion to stop the piston. After the piston has moved a sufficient distance to 80 the left, the passageways 70 will clear the cylindrical surface 58 and permit the exhaust of the air within the cylinder 52. This exhaust takes place just as the end of the plunger 44 enters the cylinder 30. The momentum of the plunger, however, is sufficient to cause the plunger to continue movement into the cylinder 30 and force all the grease contained therein past the check valve 34.

As soon as the pressure on the large face 105 of the piston 50 is lowered, the air pressure on the annular face 66 of the piston is sufficient to cause return movement thereof. This movement continues until the momentum of the return movement of the piston is 110 checked by the air which is admitted as soon as the passageways 70 again communicate with the annular space 72 formed around the piston.

The position of the piston shown in Fig. 3 115 is the extreme position taken at the end of the return stroke and illustrates the fact that the piston is cushioned by air to prevent the piston from contact with the plug 60.

The reciprocation of the piston is extremely rapid so that, when compressing such substances as a heavy grease, the flow from the container is not sufficiently rapid to fill, or even partially fill, the cylinder 30. This is especially true if air pockets happen to be 120 in the grease. In Figs. 6 and 7, I have illustrated the effect of air pockets in the grease. In compressors, as formerly made, the plunger would be drawn only a short distance 125 from the end of the cylinder so that, if, for 130

example, an air pocket were formed adjacent the end of the cylinder, as shown in Fig. 6, and the plunger withdrawn only a short distance, the plunger would fail to discharge the air. This is due to the fact that the fit between the plunger and the cylinder is not air-tight and the air would leak around the plunger as it moved into its cylinder. If, however, a sufficient amount of grease is forced in with the air, the grease will form a seal so that the air and grease together will be forced past the check-valve 34. I have discovered that this may be accomplished by providing the plunger with an extremely long stroke. This will permit the grease to close in partially on the air pockets, as illustrated in Fig. 7, so that upon the compression stroke the plunger will "scrape off" a portion of the grease, at least sufficient to form a seal between the plunger and the cylinder. As long as sufficient grease is present to form the seal the air may readily be discharged from the compressor. Figs. 6 and 7 illustrate the successive stages of the ejection of grease which has a number of air pockets therein.

In ordinary greases, impurities of various kinds are frequently present. Some of these impurities may be hard, such as metal chips, filings, and similar substances. In ordinary compressors, these impurities frequently lodge between the cylinder and plunger and thus cause the parts either to score, chip or be broken. For this reason, the plunger and the end of the cylinder are hardened sufficiently to shear any impurities which may be lodged at the edge of the cylinder and force them from the cylinder. The life of the compressor is thereby materially extended and its efficiency greatly improved even when the compressor is abused by using ordinary impure greases.

After the pressure in the conduit 41 has been built up to a predetermined maximum, the lubricant will exert a downward pressure upon the cup leather 92 and against the compression of the spring 104 until the compression on the spring 84, which holds the ball valve 82 upwardly, is sufficiently released to permit the air which passes the ball to force it downwardly against its seat 86. As soon as the ball is seated, the air pressure will maintain it firmly upon its seat. When, however, the pressure in the discharge conduit 41 is sufficiently lowered the spring 104 will force the stem 94 upwardly and compress the spring 84 until, when the spring has been compressed a predetermined amount, the ball will snap suddenly upwardly, again admitting air to the air cylinder, and thus cause actuation of the plunger pump. The pressure of the grease in the discharge conduit may thus be maintained between certain predetermined limits, depending upon the adjustment of the spring 104. When the com-

pressor is not in use, the supply of air may be shut off by means of the valve 75.

The invention is capable of wide variation within equivalent limits and I contemplate such variation as may be desirable or useful in the particular adaptation of the invention shown, or in its adaptation to other machines. I do not restrict myself in any unessential particulars, but what I claim and desire to secure by Letters Patent is:

1. In apparatus of the class described, the combination of a cylinder, a plunger reciprocable into said cylinder to discharge lubricant therefrom, the stroke of said plunger being substantially longer than said cylinder, and means for applying power to move said plunger toward said cylinder and for stopping the application of power to said plunger prior to the entrance of said plunger in said cylinder, whereby the plunger will, by the force of its momentum, displace the lubricant from said cylinder.

2. In a device of the class described, the combination of a lubricant compression cylinder, a valve normally closing one end of said cylinder, a plunger reciprocable into and a substantial distance away from the other end of said cylinder, air pressure means for moving said plunger toward said cylinder, and means for releasing the supply of air under pressure to said last-named means prior to the entrance of said plunger into said cylinder.

3. In apparatus of the class described, the combination of a cylinder, a plunger reciprocable into said cylinder to discharge lubricant therefrom, the stroke of said plunger being several times the length of said cylinder, means for applying power to move said plunger toward said cylinder, and means for stopping the application of power to said plunger prior to the entrance of said plunger in said cylinder, whereby the plunger will displace lubricant in said cylinder by the force of momentum of the plunger.

4. A lubricant compressor comprising a cylinder, a plunger reciprocable into said cylinder, and means for imparting motion to said plunger, said means being operative only during that portion of the compression stroke thereof which takes place prior to the entrance of the plunger into said cylinder.

5. Lubricating apparatus of the class described, comprising a lubricant compression cylinder, means to supply lubricant thereto, a plunger reciprocable into said cylinder, an air cylinder, an air piston reciprocable in said air cylinder, an operative connection between said plunger and said air piston, a source of air under pressure, means for admitting air to said cylinder during a portion only of the operative stroke of said plunger, and means for exerting air pressure upon said piston in a direction tending to return said plunger to normal position.

6. In apparatus of the class described, the combination of a compression cylinder, a check valve normally closing one end thereof, a supply reservoir at the other end of said cylinder, and a plunger movable into said cylinder and out of said cylinder into said reservoir, the stroke of said plunger being at least twice the length of said cylinder.

7. In a lubricant compressor, the combination of a compression cylinder, a plunger reciprocable therein to displace the lubricant therefrom, an enlarged bore at the discharge end of said cylinder, a light weight hard thin metallic disc valve having a notched peripheral edge reciprocable in said enlarged bore, and a spring within said enlarged bore normally holding said disc valve against the end of said cylinder.

8. In a device of the class described, the combination of a body casting, a plug removably secured in said body and having a cylindrical bore therein, a hardened annular shoulder sloping away from the discharge end of said cylindrical bore thereby forming an edge at the discharge end of the cylindrical bore, and a spring pressed thin metallic disc resiliently held against said edge and forming the outlet valve of said cylinder.

9. A lubricant compressor comprising an open end lubricant cylinder, an air cylinder in alignment therewith, a plunger reciprocable into said lubricant cylinder, a piston in said air cylinder, said plunger and piston being rigidly interconnected, and means operable by said piston to admit air under pressure to said air cylinder at one side of said piston during a portion only of its operative stroke and thereafter to relieve the air pressure at said side of said piston.

10. A lubricant compressor comprising a lubricant reservoir, a high pressure cylinder associated therewith, a plunger reciprocable into said high pressure cylinder, an air cylinder having an air inlet port therein, means to supply air under pressure to said inlet port, and a piston reciprocable in said air cylinder and connected with said plunger, said piston having a passageway extending therethrough, said passageway being in communication with said air inlet port during a portion only of the operative stroke of said piston.

In witness whereof, I hereunto subscribe my name this 10th day of January, 1928.
55 ERNEST W. DAVIS.
